DESIGN FOR A PORTABLE POWER-DRIVEN HAND TOOL UNIT

Fred E. Anderson, Sheridan, Oreg.

Application March 19, 1945, Serial No. 118,590

Term of patent 14 years

(Cl. D54—14)

To all whom it may concern:

Be it known I, Fred E. Anderson, a citizen of the United States, residing at Sheridan, in the county of Yamhill and State of Oregon, have invented a new, original, and ornamental Design for a Portable Power Driven Hand Tool Unit, of which the following is a specification, reference being had to the accompanying drawing, forming part thereof.

Fig. 1 is a side elevational view of a portable

power driven hand tool unit, showing my design;

Fig. 2 is a front elevational view showing my

design;

Fig. 3 is a rear view; and

Fig. 4 is an elevational view of the opposite side of said tool from that shown in Fig. 1.

I claim:

The ornamental design for a portable power-driven hand tool unit, as shown.

FRED E. ANDERSON.
